UNITED STATES PATENT OFFICE.

FRANK S. NOVOTNY, OF ST. PAUL, MINNESOTA, ASSIGNOR OF ONE-HALF TO JUSTUS C. FRENCH, OF BURLINGTON, VERMONT.

NON-REFILLABLE BOTTLE.

942,183.

Specification of Letters Patent.

Patented Dec. 7, 1909.

Application filed March 13, 1908. Serial No. 420,851.

To all whom it may concern:

Be it known that I, FRANK S. NOVOTNY, a citizen of the United States, residing at St. Paul, in the county of Ramsey and State 5 of Minnesota, have invented certain new and useful Improvements in Non-Refillable Bottles, of which the following is a specification.

My invention relates to improvements in 10 non-refillable bottles its object being to provide an improved form of closure for the bottle which will allow the contents to be freely poured therefrom but which will prevent the bottle being refilled, the object being 15 particularly to provide a construction which will be impossible to tamper with by a wire or other device.

To this end my invention consists in the 20 features of construction and combination hereinafter particularly described and claimed.

In the accompanying drawings forming 25 part of this specification, Figure 1 is a vertical transverse section through a bottle neck fitted with my invention; Fig. 2 is a similar view with the valve in open position; Fig. 3 is a section on line α — α of Fig. 1; Fig. 4 is an elevation of my device shown in position in the bottle neck; Fig. 5 is an elevation of my device partly broken away, and Fig. 6 is a sectional view of a modified construction.

In the drawings A represents a bottle and B the neck. Fitted within the bottle neck below the shoulder 2 is my improved device. As shown in Figs. 1 to 4 this device comprises an outer thimble or chamber 3 open at its upper end and having its upper edge 4 outwardly flared underneath the shoulder 2. Extending through the bottom of the chamber 3 is an inner chamber 5 having a closed upper end and opening into the bottle at its lower end. The lower end of the inner chamber 5 is formed with a shoulder 6 fitting underneath the bottom of the outer chamber 3 and separated from the surrounding wall of the bottle by an interposed cork ring 7. Fitted within the lower end of the inner chamber 5 is a tube or conduit 8 covered by a cap 9 which slides within said chamber. The inner chamber 5 is formed above the conduit 8 with openings 10 which constitute the inlet openings of the device as hereinafter pointed out.

In applying my device to a bottle it is

merely necessary to insert the same into the neck of a bottle as indicated in Fig. 4 and then flare outward the upper end of the outer cylinder 3 underneath the shoulder 2, the cork 7 closely filling the space between the lower end of the device and the surrounding wall of the neck. With the preferred form when the bottle is inverted the cap 9 will drop away from the conduit 8 as shown in Fig. 2 allowing the contents of the bottle to pass through the conduit openings 10 and the passage between the inner and outer chambers 3 and 5 to the mouth of the bottle. With the bottle in upright position any liquid poured into the bottle neck will pass through the openings 10 into the inner chamber 5 pressing on the top of the cap 9 and being thus prevented from entering the bottle. I thus secure a construction of closing valve for the bottle neck which is simple and easy of application and which will allow a free open passage for pouring out the contents of the bottle while absolutely preventing liquid being poured into the bottle.

In the modified form shown in Fig. 5 I dispense with the cap and carry the inner conduit 8 to a point above the openings 10. With this form, water poured into the neck of the bottle will rise in the space between the conduit and inner chamber 5 to a point above the openings 10 compressing the air in the upper end of the chamber 5, and being prevented thereby from passing above the top of the conduit and into the bottle.

I claim:

1. In combination with a bottle neck formed with an inner circumferential shoulder, an open top chamber flared at its outer end underneath said shoulder, a closed top inner chamber extending through the bottom of said outer chamber and communicating with the interior of the bottle, and a conduit secured in the lower end of said chamber and interspaced at its upper end from said chamber, said inner chamber being formed with side openings.

2. In combination with a bottle neck, an open top chamber secured therein, an inner closed top chamber of uniform diameter extending through the bottom of said outer chamber and communicating with the interior of the bottle, said inner chamber being formed with side openings, and a conduit secured in the lower end of said inner

chamber, said conduit terminating short of the upper end of said inner chamber and being interspaced from the side wall of said chamber.

5 3. In combination with a bottle neck formed with an interior shoulder, an open top chamber fitted within said neck below said shoulder, a closed top inner chamber extending through the bottom of said outer chamber and communicating with the interior of the bottle, said inner chamber being formed with side openings, and a valve slidably supported within said inner chamber.

10 4. In combination with a bottle neck formed with an interior circumferential shoulder, an open top chamber fitted in said neck below said shoulder, an inner closed top chamber extending through the bottom 15 of said outer chamber and communicating with the interior of the bottle, the inner chamber being provided with side openings, a conduit within the lower end of said inner chamber interspaced at its outer end from 20 said chamber, and a valve for said conduit.

25 5. In combination with a bottle neck, an

open top chamber secured therein, an inner closed top chamber extending through the bottom of said outer chamber and communicating with the interior of the bottle, a conduit in the lower end of said inner chamber interspaced at its upper end from said chamber, and a cap slidably covering said conduit. 30

6. In combination with a bottle neck formed with an inner circumferential shoulder, an open top chamber flared at its upper end underneath said shoulder, a closed top inner chamber extending through the lower end of said outer chamber and communicating with the interior of the bottle, a conduit 35 secured in the lower end of said inner chamber and interspaced at its upper end from the side wall of said chamber, said inner chamber being formed with side openings and a cap slidably covering said conduit. 40

In testimony whereof I affix my signature in presence of two witnesses.

FRANK S. NOVOTNY.
